SPRAY DEVICE FOR MOISTENING COATED PAPER

Filed Dec. 26, 1941

UNITED STATES PATENT OFFICE

2,342,536

SPRAY DEVICE FOR MOISTENING COATED PAPER

Chester A. Garrison, Comstock, Mich.

Application December 26, 1941, Serial No. 424,462

3 Claims. (Cl. 91—12)

This invention relates to improvements in spray device for moistening coated paper.

The main objects of this invention are:

First, to provide a spray device for moistening the edges of a coated paper web as the same leaves a coating machine to thereby prevent curling and wrinkling of the edges while it is subsequently suspended or festooned in drying loops without producing water spots.

Second, to provide a paper moistening device of the type described, which is extremely simple in its parts and very effective in its operation, in combination with a paper coating and feeding machine, whereby the foregoing objectionable curling or wrinkling of the edges of the 10 coated web is avoided.

Third, to provide an atomizer type spraying device or apparatus associated with a paper web feeding machine to apply moisture to the edges of a web handled by said machine, in which a single source of pneumatic pressure is employed to discharge liquid and air producing the spray in the desired state of atomization.

Further objects relating to details and economies of my invention will appear from the description to follow. The invention is defined in the claims.

A structure embodying the features of my invention is illustrated in the accompanying drawing, wherein:

Fig. 1 is a fragmentary diagrammatic view in side elevation illustrating part of a paper coating machine and a paper web feeding or handling apparatus employed in the advancing of a coated web as it leaves the coating machine, the device of my invention being illustrated in operative relationship thereto.

Fig. 2 is a fragmentary top plan view illustrating a portion of the device in operative relation to a paper web traveling thereacross.

Fig. 3 is an enlarged fragmentary view partially broken away and in vertical section to illustrate details of the atomizing spray device; and

Fig. 4 is an enlarged fragmentary view illustrating the construction of one of the atomizing nozzles of the spraying unit.

The present invention relates to a simple inexpensive spray device associated with a paper coating machine for correcting a condition which universally exists or arises in a paper web coated on one side thereof, namely, a tendency for the web to curl and wrinkle at the edges when it is coated on only one side, and to curl and wrinkle while it is suspended in drying festoons or loops. The present device includes a novel atomizing

and spraying instrumentality positioned in a manner to apply a plurality of sprays or atomized jets of water to each edge of the web as it leaves the coating machine, the spraying operation being performed in a novel manner by a simple atomization unit and spray which results in securing the desired result of preventing curling and wrinkling without producing water spots.

Referring to the drawing, the reference numeral 1 designates the discharge end of a paper coating machine in which the web 2 is coated on the upper side thereof. The reference numeral 3 designates an upright of a festooning and drying machine to which the web 2 is fed from the coating machine and in which it is suspended in loops. An upstanding bracket 4 is attached to the coating machine and between this bracket and the upright 3 there is provided a hanger rod 5 from which the spraying unit of my invention, generally designated 6, is suspended. Web carrying rolls 7, 8 are appropriately journaled on the bracket and upright 3 of the drying machine over which the web passes and by which it is suspended over the spraying unit 6.

This unit is illustrated in detail in Fig. 3 and comprises a water tank or reservoir 9, the water being indicated at 10. This tank is provided with an inlet fitting 11 through which water is supplied to maintain the desired level. This is controlled by a ball float 12 (shown in dotted lines), the operating arm 13 of which is pivoted at 14 on a fixed pivot internally of the tank. Arm 13 is offset at 15 and pivotally connected at its extremity to a flow control valve 16 which controls the supply of water through water inlet fitting 11. The parts are set so that the float will drop sufficiently to open valve 16 and admit more water to the tank prior to the time that the level of the water drops below the inner discharge end of fitting 11. In other words, the latter is always immersed in the water. The supply fitting 11 is supplied through a rubber tube 17 (see Fig. 1) connected to a suitable source of water supply 18 through a master valve 19.

Tank 11 has an open air supply fitting 20 connected thereto adjacent the top thereof, through which air is continually supplied under pressure from a suitable compressor 21 driven from the coating machine. Air supply fitting 20 is connected to the compressor through a rubber air tube 22 and in operation the water in the tank is always under a predetermined pneumatic pressure, inasmuch as the air line is con-

tinually open, while coating machine drive to compressor is in operation.

The top plate 23 of the tank has an airtight seal thereto and is provided with a plurality of openings at one side thereof arranged in a group, in which the atomizing spray nozzles 24 are disposed. In the illustrated embodiment each tank has three nozzles, there being a tank or unit adjacent each side of web 2. These nozzles are cylindrical throughout a substantial portion of their length, being open at the lower end and tapering at the upper to a conical nozzle tip above the plate 23. Said tip is provided with a small orifice 25 through which air and water in an atomized jet or spray issue and impinge the edges of the paper web 2, as illustrated in Fig. 1.

For supplying the water constituting the aforesaid spray I employ the eduction tubes or liquid jets 26 which extend from top to bottom of the tank and which have body portions 27 at the lower end thereof. These body portions are adjustably threaded in the bottom wall 28 of the tank. A lock nut 29 and washer or packing 30 secure these tubes in place and effect a watertight seal therearound.

The eduction tubes 26 are provided with adjustable needle valves 31 for adjusting the amount of water discharged to the nozzle, this water entering the tubes through radial passages 32. A packing nut 33 surrounds the same and is threaded on the extremity of the jet.

At its upper end the tube 26 is positioned closely adjacent orifice 25 and has a V notch 34 cut therein (see Fig. 4) to enable air under pressure in the tank interior, with which the open end of the nozzle communicates, to enter and impinge and atomize the water, which is forced upwardly through the eduction tube by the pneumatic and hydrostatic head thereon internally of the tank 9. A spray of any desired fineness is produced by simply manipulating the needle valve 31 to regulate the amount of water supplied.

The foregoing constitutes a simple and at the same time effective moistening device which overcomes the objection of curling and wrinkling of the edges of the web without injuring or spotting the web. I am aware that it has been proposed to moisten webs in one manner or another, as by steam or by jets of water; however, I believe that I am the first to evolve a device for discharging an atomized spray to the edges of a coated web having the simplicity and effectiveness of operation of the above described apparatus. The same may be readily and quickly installed on any conventional type of paper coating machine.

An embodiment of the invention which incorporates the principles of the invention in a highly desirable manner has been illustrated and described, though I am aware that other embodiments within the intent of the invention will suggest themselves to those skilled in the art. It should be understood that the foregoing terminology is used only descriptively rather than in a limiting sense, and with full intention to include equivalents of the features shown and described, within the scope of the following claims.

Having thus described my invention what I claim as new and desire to secure by Letters Patent is:

1. In combination with a machine for applying coating to a paper web on one side thereof and for advancing and discharging the web, a pair of spraying devices supported adjacent the

charge end of said machine on the uncoated side of the web at either edge thereof, said devices each comprising a liquid containing tank provided with a plurality of atomizing spray nozzles arranged in a group to direct a spray against the adjacent edge of the web, the inner end of said nozzles opening to the interior of the tank, float valve controlled means for supplying liquid to said tank, means for supplying air under pressure to said tank to build up a predetermined pneumatic pressure on the liquid therein, said nozzles being internally exposed to said pneumatic tank pressure whereby air issues therefrom and having eduction tubes associated therewith which are in communication with the liquid beneath the surface thereof whereby liquid is forced under pneumatic and hydrostatic head through the tubes and nozzles and is atomized by the air issuing therefrom.

2. The combination with a machine for applying coating to a paper web on one side thereof and for advancing and discharging the web, a pair of spraying devices supported on the uncoated side of the web, and adjustable transversely of the path of travel of the web, said devices each comprising a liquid containing tank provided with a plurality of spray nozzles arranged in a group, the nozzles of the group being spaced relative to each other transversely of the web, to direct a spray against the adjacent edge of the web, the inner ends of said nozzles opening to the interior of the tank, means for supplying liquid to the tank, means for supplying air under pressure to said tank to build up pneumatic pressure on the liquid therein, said nozzles being internally exposed to the pneumatic tank pressure whereby air issues therefrom, and having eduction tubes associated therewith which are in communication with the liquid beneath the surface thereof whereby liquid is forced under pneumatic and hydrostatic head through the tubes and nozzles and is atomized by the air issuing therefrom, each of said eduction tubes being provided with a regulating valve whereby the amount of liquid and character of the spray discharged from each nozzle may be controlled independently of the other nozzles.

3. In combination with a machine for applying coating to a paper web on one side thereof and for advancing and discharging the web, a spray device supported on the uncoated side of the web and adjacent an edge thereof, said device comprising a liquid containing tank provided with a plurality of atomizing spray nozzles arranged in a group, the nozzles of the group being spaced transversely of the path of travel of the web, the inner ends of the nozzles opening to the interior of the tank, means for supplying liquid to said tank, means for supplying air under pressure to said tank to build up pneumatic pressure on the liquid therein, said nozzles being internally exposed to the pneumatic tank pressure whereby air issues therefrom, and having eduction tubes associated therewith which are in communication with the liquid beneath the surface thereof, whereby liquid is forced under pneumatic and hydrostatic head through the tubes and nozzles and is atomized by the air issuing therefrom, and means for independently varying the spray discharged by each nozzle to provide a decreasingly varying amount of moisture from the edge of the web inwardly.

CHESTER A. GARRISON.
